[57] CLAIM

The ornamental design for a gutter drain, as shown and described.

DESCRIPTION

FIG. 1 is a top, end, and side perspective view of a gutter drain showing my new design; FIG. 2 is an enlarged end elevational view thereof, the opposite end being a mirror image of that shown; FIG. 3 is a side elevational view thereof, the opposite side being a mirror image of that shown; FIG. 4 is a top plan view thereof; and, FIG. 5 is a bottom plan view thereof.

FIG. 1

FIG. 2

FIG. 3

FIG. 4

FIG. 5
